UNITED STATES PATENT OFFICE.

CARL SENN, OF STOCKTON, CALIFORNIA, ASSIGNOR OF ONE-HALF TO J. JEROME SMITH, OF STOCKTON, CALIFORNIA, AND ONE-FOURTH TO DAVID C. DEMAREST, OF SAN FRANCISCO, CALIFORNIA.

SELF-LUBRICATING AIR-COCK FOR ROCK-DRILLS.

933,675.

Specification of Letters Patent. Patented Sept. 7, 1909.

Application filed August 17, 1908. Serial No. 448,891.

To all whom it may concern:

Be it known that I, CARL SENN, a citizen of the United States, residing at Stockton, in the county of San Joaquin, State of California, have invented certain new and useful Improvements in Self-Lubricating Air-Cocks for Rock-Drills; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in mining machinery and particularly to air cocks used in connection with rock drills, the object of the invention being to produce an air cock adaptable for pipe lines leading to rock drills or similar machines which employ a fluid pressure such as compressed air or steam, which cock shall have in combination with its functions as a valve, a means or mechanism for oiling the valve and all parts of the machinery every time the valve is closed and opened again.

A further object is to produce such oiling means in a simple and effective manner and one capable of regulating the passage of the oil according as it is needed, as for instance when starting the machine very little oil or none at all would be needed.

These objects I accomplish by means of a valve comprising a valve casing having main outlet and inlet ports and an oil chamber, a freely turnable hollow plug in said casing having main ports to communicate with the main ports of said casing, ports adapted to communicate from the upper end of said oil chamber to the interior of said plug when the valve is open, ports adapted to communicate from the bottom of said oil chamber to the interior of said plug when the valve is closed, and ports adapted to communicate from the interior of said plug to the atmosphere prior to the communication of said last named ports.

The principle employed in the device is to use the live pressure passing through the open valve to compress the oil in the oil chamber by deflecting some of the air pressure through the first named ports, and when the valve is closed the pressure within

the hollow plug is relieved to the atmosphere and the pressure in said oil chamber forces oil through said second named ports into said hollow plug until the pressure in the oil chamber and plug is equalized. Then when the valve is opened again, the air or steam passing through such hollow plug picks up the oil and carries to the machinery, the valve itself being also oiled thereby. Such other and further construction and relative arrangement of parts are employed as will appear by a perusal of the following specification and claims.

In the drawings similar characters of reference indicate corresponding parts in the several views.

Figure 1 is a vertical section of the improved valve showing the ports open. Fig. 2 is a cross section of the valve taken at right angles to the section shown in Fig. 1 showing the main ports closed. Figs. 3 and 4 are similar views showing a modified type of valve employing the same principle. Fig. 5 is a sectional view taken relatively on a line *x-x* of Fig. 1 looking upward. Fig. 6 is a sectional view taken relatively on a line *y-y* of Fig. 3 looking upward.

Referring now more particularly to the characters of reference on the drawings 1 designates the casing of the valve having the usual main inlet and outlet ports 2 and 3. Formed on the lower end of said valve seat is an oil chamber 4 having a plugged inlet 5 and a removable bottom cap 6.

7 designates the valve plug which is hollow and inserted in the head 1 and having main ports 8 and 9 to align with the main ports 2 and 3 to open the valve. A spiral spring 10 bears between the bottom of the plug 7 and the cap 6 to maintain the plug in position.

Ports 11 lead from the chamber 4 and register with a port 12 in the plug 7 when the valve is open thus permitting the oil 13 in the chamber 4 to become under pressure from the air or steam passing through said valve. I have provided two of the ports 11 oppositely disposed so that either one will register with the port 12 no matter in which direction the valve is opened.

When the valve plug 7 is operated to just close the ports 9 and 3 and 8 and 2, a port 14 in the plug 7 registers with an atmospheric port 15 in the head 1 thus releasing

the pressure from within the plug to the atmosphere. Then when the port 12 is turned at substantially right angles to the ports 2 and 3 it registers with a port 16 leading 5 from the bottom of the chamber 4 which permits the compressed air to blow a little oil into the hollow plug 7 until the pressures in said plug 7 and said oil chamber 4 are equalized, the ports 14 being out of register with 10 the ports 15 during this operation. Then when the valve is again opened the air or steam passing through the plug 7 picks up this oil and carries to the various parts of the machinery. I also provide two ports 16 as 15 well as two ports 11 so that the oil will be admitted no matter in which way the valve is operated. If no oil is needed for the machinery then the plug 7 may be turned just to the lapped position described and then 20 back again to open position without permitting any entrance of oil. I provide four ports 14 two on each side of the plug 7 to insure the atmospheric escape no matter in what position the valve is turned.

25 Figs. 3, 4 and 6 are views showing a modified form of the device from that shown in Figs. 1, 2 and 5. In these views there is an oil chamber 17 in the bottom of the casing 30 1^a and another one 18 above the casing, the two communicating with each other by means of a port 19 in the side of the casing. When the valve is open a port 20 communicates from the interior of the plug 21 to the chamber 18 thus placing the oil therein 35 under compression. Then when the valve is closed the port 20 in the plug 21 registers with one of four atmospheric bleed ports 22 in the side of the casing 1^a to permit the escape of the air pressure therein, and then 40 when the valve is further closed a port 23 in the plug 21 communicates with the port 19 and the pressure on the oil forces a little into the interior of the plug 21.

45 From the foregoing description it will be readily seen that I have produced a device which substantially fulfills the object of the invention as set forth herein.

While this specification sets forth in detail 50 the present and preferred construction of the device still in practice such deviations from such detail may be resorted to as

do not form a departure from the spirit of the invention.

Having thus described my invention what 55 I claim as new and useful and desire to secure by Letters Patent is:—

1. A valve casing having main ports and an oil chamber, a valve in said casing comprising a hollow plug freely turnable in said valve casing and having main ports to register with the main ports of said valve casing, means for placing the oil in said chamber under air compression when the valve is opened, and means for admitting said oil 60 65 into the plug when the valve is closed.

2. A valve casing having main ports and an oil chamber, a valve in said casing comprising a freely turnable plug having main ports to register with the main ports in said casing, means admitting air under pressure to said oil chamber when the valve is opened, means relieving the pressure in said plug when the valve is just closed, and means for admitting said oil from said oil chamber 70 75 into said plug after the relieving of the pressure therein.

3. A valve casing having main ports and an oil chamber, a turnable valve plug in said casing having a main port to register 80 with said main ports in the valve casing, said plug having an oil pocket with an oil feed port in the plug discharging into said pocket, and the casing having two ports entering the oil chamber and registerable with 85 said oil feed port in the plug, said pocket in the plug opening into said main ports in the valve casing when the valve is open.

4. The combination of a valve casing having main ports and an oil reservoir, a plug 90 having a port communication with said main ports in the valve casing, said plug and casing having means for admitting air pressure to the oil reservoir when the valve is turned in one direction, and for admitting oil to the valve ports from the reservoir when the valve is turned in the opposite direction.

In testimony whereof I affix my signature in presence of two witnesses.

CARL SENN.
